UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

WORK-GAUGING MEANS FOR SEWING MACHINES.

Application filed September 20, 1924. Serial No. 738,752.

This invention relates to sewing machines and has for an object to provide work-gauging mechanism including laterally movable work-engaging elements which 5 occupy inoperative or out of the way positions when work is being introduced to the machine, and are subsequently moved to operative positions without special attention on the part of the operator. More particularly, the invention has for an object to 10 provide work-gauging means for the work-clamp of a buttonhole sewing machine to facilitate the rapid working of accurately centered buttonholes in straps of various 15 kinds such, for example, as sandal or suspender straps.

According to the present improvement, the work-support of the machine is provided with a pair of reciprocally and laterally 20 movable work-centering gauges which are connected to be operated by the usual upwardly and downwardly movable work-engaging device which is lowered into engagement with the work to hold the latter 25 for the action of the stitch-forming mechanism. In certain types of sewing machines, such as straight-away stitching machines, the upper work-engaging device is known as a presser-foot and the work is fed relatively to such foot between consecutive penetrations of the sewing needle. In other 30 types of sewing machines, such as group stitching machines, the upper work-engaging device is constituted by one or more clamping 35 feet which move with the work to position the stitches. When the work is to be removed from or introduced to the machine, the upper work-engaging device is customarily raised, and the gauges, through their 40 connection with such device, are spread apart and shifted to their inoperative positions. After the work is introduced to the machine and as the upper work-engaging device is being lowered into engagement 45 with the work, the gauges are laterally moved to engage and center the work before the work is gripped by such device. Where the gauging mechanism is applied to a buttonhole sewing machine to center the 50 shanks of strap-ends, it is desirable to provide one or more strap-end gauges defining a pocket or the like for centering the strap-end.

To adapt the mechanism for centering

straps of various widths, the connection between the reciprocally movable gauges and the mechanism for operating the upper work-engaging device may be made yielding in character, so that such device may continue its motion to fully engage and press 60 upon or clamp the work after the motion of the centering gauges is arrested by the work.

In the accompanying drawings, Fig. 1 is 65 a plan view of the work-clamp of a button-hole sewing machine embodying the invention. Fig. 2 is a similar view with the upper work-clamping feet removed and showing the work in sewing position. Fig. 3 is a section on the line 3, 3, Fig. 1, and Fig. 4 is a perspective view of one of the stationary gauges.

By way of illustration, the invention is disclosed as embodied in the work-clamp of a group stitching machine of the buttonhole type constructed substantially in accordance with the disclosure of the patent to Allen, No. 1,331,176, of February 17, 1920. A work-clamp of this type comprises a longitudinal slide-frame 1 including the cross-bar 2 which passes through and slidably carries the downwardly projecting lugs 3, 3, formed on the cross slide-plate 4. Secured to the upper side of the front-end portion of the cross slide-plate 4 is the transversely extending retainer plate 5 the rearward edge of which overhangs the flanges 7 at the front edges of the lower work-supporting plates 8 of the laterally separable sections of the work-clamp. Disposed above the work-supporting plates 8 are the upper work-engaging devices or work-clamping feet 9 carried at the free ends of the usual clamping arms 10, which are pivotally mounted at 11 on the fulcrum-blocks 12 carried by the plates 8. The upper work-engaging means or clamping feet are operated by the usual lifting and lowering mechanism including the separably connected rock-shaft sections 13 carrying cam-elements 14, a finger-lever 15 and a rearwardly extending lever 16 adapted to be depressed automatically by suitable mechanism when the machine is started; such mechanism being disclosed, for example, in the patent to Allen, No. 15,324, reissued April 4, 1922.

The lower work-supporting plates 8 and upper work-engaging means or clamping

feet 9 are, in the present embodiment of the invention, apertured to expose an area of the work to the stitch-forming mechanism; such apertures being shown in the form of key-hole slots 17, 18, adapted for the working of eyelet-end buttonholes.

The buttonhole cutting and stitch-forming instrumentalities of the machine work through these slots in the work-clamp and it is necessary that the work be carefully positioned relative to such slots if the finished buttonhole is to appear where wanted. In working buttonholes in strap-ends, it is essential to sightly work that the buttonholes be located at uniform distances from the extreme ends of the straps, and also that the center lines of the buttonholes coincide with the center lines of the corresponding straps.

The strap-end gauging means comprises the gauge-blocks 19 which are secured to the respective arms 20 having their shanks slotted at 21 for passage of fastening screws 22 threaded into the plates 8. The gauge-blocks have their proximate edges 23 inclined to form a V-notch which serves to uniformly position and center the strap-ends 24.

The strap-shanks are centered by means of the reciprocally movable gauge-levers 25, 26 fulcrumed at 27, 28 on the fulcrum block 29 secured to the retainer plate 5. The gauge-levers 25, 26 overhang the work-supporting plates 8 of the removable clamp-sections and terminate at their free ends in the upwardly bent toes 30 adapted to engage the side edges of the work-piece.

Mounted in the slideway 31 in the block 29 is the slide-block 32, which is connected to the gauge-levers 25, 26 by means of links 33, 34 of equal length. The link 34 has an extension constituting a lever-arm 35 by means of which the slide-block is reciprocated and the gauge-levers 25, 26 reciprocally moved. The linkage is such that the toes 30 of the levers 25, 26 are equi-distant from the center line of the clamp for any position of the slide-block 32. Thus, when said levers are closed into engagement with a strap-shank they will center it relatively to the work-clamp regardless of its width.

The gauge-levers 25, 26 are preferably connected to be operated by the clamp-closing mechanism to insure the centering of the work without special attention on the part of the operator. To this end, one of the rock-shaft sections 13 has fixed thereto a depending arm 36 to which is freely pivoted the rearward end of the rod 37, the forward end of which is telescopically received within the rearward end of the tubular rod 38 pivotally connected at 39 to the lever-arm 35. A light spring 40 is disposed within the tubular rod 38 in engagement with the forward end of the rod 37. When the rock-shaft sections 13 are turned to close the

work-clamp, the gauge-levers 25, 26 are moved toward one another until the toes 30 engage and center the work. Further approach of the gauge-levers is arrested by the work while the spring 40 yields, so that the turning of the rock-shaft sections 13 fully to clamp-closing position will not force the gauge-levers to distort the work.

A screw 41 passing through the slot 42 in the tubular-rod 38 and threaded into the rod 37 prevents over extension of the rods 38 and 37 and affords a lost-motion positive connection between such rods. The timing is such that the gauge-levers are moved to their work-centering positions before the upper clamping feet 9 grip the work. It will be observed that the gauge-levers 25, 26 do not interfere in any way with the lateral or usual spreading movements of the clamp-sections.

A cover-plate 43 having a strap passage-way 44 is provided to cover the gauge levers 25, 26 and prevent fouling of the work therewith.

The invention is not to be understood as limited in its application to a buttonhole sewing or other type of group-stitching machine, as it is obviously applicable in its broader aspects to straight-away stitching machines.

Having thus set forth the nature of the invention, what I claim herein is—

1. In a sewing machine, the combination with the upper and lower work-clamping elements and clamp-closing mechanism, of reciprocally movable work-centering elements operatively connected to said clamp-closing mechanism.

2. In a group-stitching machine, the combination with the work-supporting means, clamping feet and clamp-closing mechanism, of strap-end gauging means disposed adjacent said clamping feet, and reciprocally movable strap-shank gauges connected to be operated by said clamp-closing mechanism.

3. In a group-stitching machine, the combination with the work-supporting means, clamping feet and clamp-closing mechanism, of strap-end gauging means disposed adjacent said clamping feet, reciprocally movable strap-shank gauges, and a yielding operative connection between said gauges and said clamp-closing mechanism.

4. In a sewing machine, the combination with work-supporting means, vertically movable work-engaging means and operating means therefor, of laterally movable work-gauging means disposed adjacent said work-engaging means, and a cover-plate for said work-gauging means formed with a strap passageway.

5. In a group-stitching machine, the combination with the work-supporting means, clamping means and clamp-closing mechanism, of a pair of pivotally mounted gaug-

ing levers, and means connected to said clamp-closing mechanism for simultaneously moving said levers in opposite directions to gauging position.

5 6. In a group-stitching machine, the combination with the work-clamp support and removable work-clamp sections, of work-gauging arms pivotally mounted on said support and overlying but free of connection with said sections.

10 7. A work-clamp for group-stitching machines having upper and lower work-clamping elements apertured to expose an area of the work to the action of the stitch-forming mechanism, clamp-closing means, a slide-

block movable in a path in line with said apertures, gauge mechanism including gauging-levers fulcrumed on opposite sides of said path, means including link connections between said slide-block and levers 20 for reciprocally moving the latter, and an operative connection between said clamp-closing means and said gauge mechanism for moving said gauge levers to gauging position during the clamp-closing movement of 25 said clamp-closing means.

In testimony whereof, I have signed my name to this specification.

EDWARD B. ALLEN.
